[57] CLAIM

The ornamental design for an electro-mechanical equipment housing for scales or the like, as shown and described.

DESCRIPTION

FIG. 1 is a top and right front perspective view of an electro-mechanical equipment housing for scales or the like showing our new design, the broken-line showing of a counterstop being environmental only and forms no part of the claimed design;

FIG. 2 is a top and right rear perspective view thereof;

FIG. 3 is a left side elevational view thereof;

FIG. 4 is a bottom plan view thereof.
